DISPLAY FIXTURE

Robert L. Mapson, Los Angeles, Calif., assignor
to M. & D. Display Mfg. Corporation, Los
Angeles, Calif., a corporation of California

Application July 27, 1935, Serial No. 33,445

3 Claims. (Cl. 211—128)

My invention relates to apparatus for displaying merchandise and has particular reference to a step fixture for use on display counters.

In stores retailing small articles of merchandise such as hardware, notions, etc., it is customary to provide counters upon which the merchandise is displayed. Suitable means is provided on the counters for forming compartments or bins such as disclosed in Patent No. 1,911,377 issued to me May 30, 1933 and is also somewhat similar to my copending application, Serial No. 716,191 filed March 17, 1934, (now Patent No. 2,048,802).

It is also advantageous in displaying small articles to provide elevated or step fixtures on the counters for displaying certain merchandise above the level of other merchandise on the counter. It has been found in practise that the sale of merchandise can be appreciably increased by displaying the goods in step fixtures. In this manner the articles so displayed are more readily noticed by the customers, and articles that do not sell readily can be more quickly disposed of when displayed in such a fixture.

The step fixtures in present use are either permanently constructed of wood or are built up by superposing inverted boxes. Neither of these methods of constructing step fixtures is entirely satisfactory as the permanent ones cannot be readily changed in size to meet future requirements and the built up type is not rigid and requires considerable skill in the formation thereof.

An object of my invention is to provide a step fixture that may be readily taken apart or assembled, the disassembled parts thereof making a compact package for shipment.

Another object of my invention is to provide a step fixture that may be readily disassembled yet one that is as rigid and substantial as a permanent fixture when assembled for use.

A further object of my invention is the provision of a step fixture upon which compartments or bins of different sizes may be readily formed.

Still another object of my invention is the provision of a step fixture that can be varied in width.

A further object of my invention is the provision of a clip for supporting relatively high glass partitions on a display fixture.

Other objects and advantages will become apparent in the following description taken in connection with the accompanying drawings, in which:

Fig. 1 is a perspective view of a preferred form of fixture of my invention.

Fig. 2 is a longitudinal, vertical sectional view of the unit shown in Fig. 1.

Fig. 3 is an enlarged transverse sectional view taken on the line 3—3 of Fig. 1.

Fig. 4 is a perspective view of some of the parts of the fixture shown in Fig. 1 as they appear when disassembled.

Fig. 5 is an enlarged, fragmentary, horizontal sectional view taken on the line 5—5 of Fig. 1.

Fig. 6 is a view similar to Fig. 3 showing the manner in which the fixture shown in Fig. 1 may be increased in width.

Fig. 7 is an enlarged plan view of a portion of the fixture shown in Fig. 1.

Fig. 8 is an enlarged perspective view of one of the corner clips shown in Fig. 1.

Fig. 9 is a detail perspective view of the removable cap shown on the clip in Fig. 8 and

Fig. 10 is a fragmentary perspective view of the upper end of the clip shown in Fig. 8.

Referring specifically to the drawings, a step fixture 10, comprising a preferred embodiment of my invention, is shown in Figs. 1 and 2, this fixture including tray supporting members 11, a back wall 12, trays 13 and 13a and compartment 14 forming apparatus 14.

The tray supports 11, one of which is shown in detail in Fig. 4, are identical excepting that one is right hand and the other left hand. Each of the supports 11 includes an outside and inside sheet of metal 15 and 16 respectively having flanges 17 and 18 at their lower edges, the flanges 17 and 18 being spot welded or otherwise secured together. Formed integral with the outside sheet 15 are tabs 19, 20, 21 and 22, the latter being formed so as to retain the sheets 15 and 16 in proper spaced relationship. As shown in Fig. 4 the upper edges of the sheets 15 and 16 are cut to provide progressively higher steps 24, 25 and 26.

The back wall 12 is formed of a single sheet of metal to provide a bottom flange 30 and side flanges 31, the latter being cut at their upper ends to provide notches 32. As seen in Figs. 2 and 4, the upper edge of the wall 12 is return bent and formed to provide a channel 33.

The trays 13, one of which is shown in Fig. 4, are each formed of a single sheet of metal to provide a top 35, end flanges 36, a rear flange 37 and a front flange 38, the latter being return bent at its lower edge to provide a channel 39. The entire top 35 of each of the trays 13 is formed to provide a regular pattern of square apertures 40 as shown in Fig. 7.

The lowermost or front tray 13a is identical to the trays 13 excepting that the front wall 38a

thereof is of less height than the walls 38 of the trays 13 and is inwardly bent at its lower edge to provide a flange 42.

The compartment forming apparatus 14 includes high corner clips 44, low corner clips 45 and right and left hand one-way clips 46 and 47 respectively. Each of the aforementioned clips has suitable lugs for interlocking engagement with the perforated tops 35 of the trays 13 and 13a substantially as set forth in the above referred to patent and copending application. Received and supported by the various clips are high and low glass partitions 48 and 49 respectively as shown in Fig. 1.

Referring now to Figs. 8, 9 and 10, I have shown therein the details of one of the high corner clips 44. This clip, which is particularly adapted for use on the high glass partitions 48, includes a base 50 having lugs 51 formed thereon for engagement with the apertures 40 as seen in Fig. 7. Formed integral with and extending upward from the base 50 is an outside angle 52, and welded or otherwise secured on the base 50 is an inside angle 53, the latter being formed at its upper end to provide arcuate portions 54. Removably mounted on the upper end of the clip 45 is a cap 60, the latter being formed of one piece of metal to provide vertical walls 61 and yieldable fingers 62, the latter being formed to engage the arcuate portions 54 of the inside angle 53 as shown in Fig. 8.

Operation

The respective parts of the step fixture 10 are assembled in the following manner: The back wall 12 is secured to the rear ends of the tray supporting members 11 by inserting the upper ends of the flanges 31 in between the sheets 15 and 16 so that the rearmost edges of the tabs 22 are received by the notches 32. The wall 12 then being swung into the position in which it is shown in Fig. 2 with the flanges 31 thereof fully received between the sheets 15 and 16 of the members 11.

The uppermost tray 13 is then mounted on the members 11 as shown in Figs. 1 and 2 with the end flanges 36 of the tray being received between the sheets 15 and 16, it being noted that the rear flange 37 of the tray is received and supported by the channel 33 of the back wall 12. The center tray 13 is mounted in the same manner, with the rear flange 37 thereof being supported by the channel 39 of the front flange 38 of the uppermost tray 13. The front tray 13a is positioned in the same manner and the compartment forming apparatus 14 positioned on the trays 13 and 13a as shown in Fig. 1.

Each of the clips 44, 45, 46 and 47 is mounted by inserting the lugs thereof into the desired apertures while the clip is held in a substantially horizontal position, the clip being then raised to vertical position as shown and described in the above referred to patent and copending application. The glass 48 and 49 is inserted into pairs of the clips thus retaining the latter in interlocking engagement with the trays. After the high glass 48 is inserted into the corner clips 44 the caps 60 are snapped into position and retained thereon by engagement of the fingers 62 with the arcuate portions 54 of the inside angle 53. The caps 60 serve to retain the angles 52

and 53 against the glass and greatly increase the strength of the clip as well as improving the general appearance of the fixture.

Although I have shown high and low glass in the fixture 10 it is understood that either one may be used throughout the unit or in any desirable combination to suit the requirements of the merchandise to be displayed thereon.

Referring now to Fig. 6, I have shown therein the manner in which a fixture 65 of greater width than the fixture 10 may be built with the apparatus of my invention. Sufficient space is provided between the sheets 15 and 16 of the supports 11 to receive the flanges 36, of two trays 13 or 13a placed end to end as shown, it being obvious that any desired number of the trays may be placed end to end as shown in Fig. 6.

Although I have shown and described but one preferred form of my invention it is to be understood that many modifications and changes might be made therein without departing from the spirit of the invention or the scope of the following claims.

I claim as my invention:

1. In a display fixture, the combination of: a pair of supporting members cut on their upper edges to form steps of progressively higher levels, each of said members comprising a pair of spaced sheets of metal, one of said sheets having tab portions for engaging and retaining the adjacent sheet in said spaced relation; and a tray extending between said supporting members at each of said steps, each of said trays having downward bent flanges at opposite ends thereof, said flanges being received and supported between the spaced sheets of said supporting members.

2. In a display fixture, the combination of: a pair of supporting members, each of said members comprising a pair of closely spaced sheets of metal cut at their upper edges to form a series of steps; a tray extending between said supporting members at each of said steps, each of said trays comprising a flat sheet of metal having downturned flanges on the front, rear and end portions thereof, the flanges at the ends of said trays being received and supported between the spaced sheets of said supporting members at said steps, the flanges on the rear edges of all but the uppermost of said trays being received and supported by upturned portions on the lower edges of the flange on the front edges of said trays.

3. In a display fixture, the combination of: a pair of supporting members cut on their upper edges to form steps of progressively higher levels, each of said members comprising a pair of spaced sheets, one of said sheets having tab portions for engaging and retaining the adjacent sheet in said spaced relation; a tray extending between said supporting members at each of said levels, each of said trays comprising a flat sheet having downturned flanges on the front, rear and end portions thereof, the flanges at the ends of said trays being received between spaced sheets of said supporting members at said steps, the flanges on the rear edges of all but the uppermost of said trays being received and supported by upturned portions on the lower edges of the flanges on the front edges of said trays.
